SEPARABLE FASTENER

Louis H. Morin, Bronx, N. Y., assignor to White-hall Patents Corporation, Bronx, N. Y., a corporation of New York

Application March 31, 1939, Serial No. 265,092

4 Claims. (Cl. 24—205)

This invention relates to separable fasteners comprising stringer tapes with coupling links thereon, with a slider movable along the stringers to couple and uncouple the links. More particularly, the invention relates to the construction of the stringer tapes and especially the edge portion of the tape to which the links are attached or applied, as well as the method of constructing the fastener stringers in a continuous operation in accordance with the method defined. The novel features of the invention will be best understood from the following description and annexed drawing in which certain embodiments of the invention are disclosed and in which the separate parts are designated and suitable reference characters in each of the views, and in which:

Fig. 1 is a plan view of a part of a separable fastener made according to my invention.

Fig. 2 is a diagrammatically sectional view illustrating the method of applying links to a stringer tape made according to the invention.

Fig. 3 is a sectional view substantially on the broken line 3—3 of Fig. 2.

Fig. 4 is an enlarged sectional view on the line 4—4 of Fig. 2.

Fig. 5 is an enlarged perspective view of a part of a stringer tape showing one adaptation of the invention.

Fig. 6 is a view similar to Fig. 5 showing another adaptation of the invention; and,

Fig. 7 is a cross-sectional view of a strip such as shown in Fig. 6 illustrating a link arranged thereon.

To illustrate the type of device in connection with which my invention relates, I have shown in Fig. 1 of the drawing a part of a separable fastener consisting of two stringer tapes 10, 10a. Arranged longitudinally of one edge portion of the tapes 10, 10a are cords or strands 11, 11a forming enlarged or beaded edges on said tapes. At 12, 12a are shown coupling links or scoops attached to the beaded edges of the tapes in spaced relationship and in such manner that the stringers may be coupled and uncoupled by a slider 13 movable longitudinally thereof, as in other devices of this kind. At 14 is shown an end stop at one end of the tapes for coupling the tapes together and for limiting the movement of the slider in one direction on the stringers. At 15 is shown part of a pull coupled with the slider to facilitate operation thereof.

In carrying my invention into effect, I may simply use plain cords or strands, of any type and kind of material arranged longitudinally of

the edge portion of the stringer tape. In attaching certain types and kinds of links to the tape, it is desirable to use cords or strands including either a wire or a rayon or other strand, spirally wound on the cords or otherwise forming a part thereof, to be exposed at sufficiently close intervals to contact each of the links applied thereto. In employing a metal strand or wire, this is employed to facilitate electroplating of metallic links attached to the stringer tapes, whereas in using rayon or other strands these are employed to facilitate a more secure attachment of plastic or thermoplastic links applied to the tape. In Fig. 5 of the drawing a part of the stringer tape 10 is shown, and 11 represents the cords arranged on opposite surfaces of the tape 10 at the edge portion 16 thereof, and at 17 is indicated the wire or rayon strands spirally wound upon the cords 11. The edge 16 of the tape may be made slightly enlarged in the process of weaving the same so as to retain the cords 11 against displacement after the links have been applied as later described. However, in some instances and where pressure is applied to the cords in attaching the links thereto, the enlargement of the edge 16 will not be essential.

Contrasting to the result of the arrangement shown in Fig. 5, in Figs. 6 and 7 of the drawing is shown a stringer tape 10b, upon which plain cords 11b are arranged, and substituted for the strands 11 is what is termed a tinsel strand 18 which consists of nothing more or less than a fine cotton or other cord upon which is spirally wound a wire 19. It will be apparent, however, that the winding on the strand 18 may be in the form of a rayon or other thread. The strand 18 is laid longitudinally of the edge 16a of the tape so that the strand 18 or the wrapping 19 thereon will be exposed for contact with each of the links or scoops applied to the strip 10b as at 12b of Fig. 7 of the drawing.

At this point it will be well to mention that, while the cords or strands 11 are shown as wound in cross-sectional form, they may in actual practice assume an irregular contour by virtue of the compression of the links thereon, and in some instances this would operate to compress the strip to form slight depressions therein as indicated at 20 in Fig. 7 of the drawing. The links of the separable fastener may be formed in any desired manner and attached in any way, but in making these links as die castings, they may be cast directly upon the tape as is now well known in this art.

To illustrate one method of carrying the invention into effect, I have shown in Figs. 1, 2, 3, and 4, more or less diagrammatically, parts of the machine forming the subject matter of my prior application Ser. No. 189,309, filed April 8, 1938. In Fig. 2, 21 represents the upper, discharge end, of a gooseneck 22 forming the discharge nozzle through which the casting material is injected into the impression 23 of relatively movable dies 24, 24a supported in die operating members 25, 25a, part of which are shown in Figs. 2 and 4. The dies 24, 24a are so constructed as to receive a stringer tape 10 as well as the beaded edge formed by the cords 11 thereon, the latter entering the impression 23 to facilitate the formation of the cast links 12 thereon. A core pin 26 is also supported by the dies, 24, 24a and extends into the impression 23 so that each casting 12 is formed thereon, and this pin movable by its supporting arm 26a serves to feed a cast link as well as the tape for the close spacing of the links on the tape, as taught in the application hereinbefore referred to. The wide spacing of the links or groups of links on the tape, as for example at 27, Fig. 2 of the drawing is accomplished by a tape feeding mechanism 28 supported through the medium of a bracket 29 on an operating rod 30, the mechanism 28 having grippers 31 for engaging and feeding the tape 10 in the wide spacing of the tape, again as taught in said prior application. These structures are here illustrated simply to show one method of carrying my present invention into effect. At 32 is shown a guide roller or spool over which the tape 10 passes and this tape is guided through the feed mechanism 28 prior to entering the dies 24, 24a. According to my present invention, I also employ other suitable guide rollers 33 for guiding the strands or cords 11 onto opposite surfaces of the tape 10 at one edge portion thereof. The mechanism 28 will serve to maintain the proper location of the cords 11 with respect to the edge 16 of the tape in entering the impression 23 of the dies, the said mechanism having a downwardly extending portion 28a which terminates in close proximity to the dies 24, 24a as will be apparent.

From the foregoing description, it will be apparent that the cords or strands 11, 11b, are simply guided into and through a machine employed for attaching links or scoops to one edge of the tape without attaching the cords to the tape other than through the medium of said links. This eliminates the necessity of using expensive stringer tapes where the enlarged or beaded edges are integrally woven with the tape in the production thereof, or where such enlarged portions are formed by cords or strands stitched to the stringer tape. It will thus be seen that a very economical way of tape construction is provided and as the tape cost is one of the outstanding costs in the manufacturing of fasteners of the type and kind under consideration, it will appear that a material saving will be effected by constructing a device in accordance with the method herein defined.

In employing the construction shown in Fig. 6, it will of course be apparent that the tape guide will be constructed so as to receive and guide the strand 18 for proper location on the outer surface of the edge 16a and suitable means will be provided for guiding the strands into a machine.

It will be understood that while I have shown, in Figs. 2, 3, 4, one method of constructing and

applying links to the tape, that this is solely to illustrate one adaptation of the invention. Where the links have been pre-formed and are then compressed and otherwise attached to the tape, suitable means will be provided for guiding the tape and strand into machines of this type and kind.

It will be understood that the cords or strands 11, 11b may be composed of any suitable material and of any desired cross-sectional form. In some instances these strands may in their entirety be composed of a wire preferably of the flexible type. In other words, my invention does not depend upon any particular type of strand or any particular structure thereof, but rather in the laying of some type or kind of elongated strip or strand longitudinally over one edge portion of a tape for the purpose of enlarging this edge portion to form what is commonly referred to as a beaded edge which aids in securing the links against displacement from the tape. While I have shown in the accompanying drawing, two strands laying one at each side portion of the tape, it will of course be apparent that a single strand may be employed.

In forming die cast links upon a tape of the kind here under consideration and especially when the links are composed of metallic castings, it will be understood that the molten metal will extend into the interstices of the braid of the tape, as well as into the interstices or crevices of the strands arranged thereon to secure and support the links in position. This result is accomplished by virtue of the pressure injection of the heated molten material into the impression of the dies. It will be apparent that in attaching links of any kind to the corded edges of the tapes, as disclosed, sufficient friction is established between the cords and the tapes to securely retain the links against displacement. This is further amplified by reason of the enlargement of the edge 16, 16a of the tape. Therefore the tapes become as strong as other types and kinds of beaded edge tapes.

Having fully described my invention, what I claim as new and desire to secure by Letters Patent, is:

1. In a separable slide fastener comprising fastener stringers adapted to be coupled and uncoupled by a slider movable longitudinally thereof, each of said stringers comprising a woven stringer tape, an independent strand loosely arranged longitudinally of one edge of the tape in forming a beaded edge on the tape, die cast coupling links fashioned directly on said edge of the tape and engaging said strand in supporting the strand on the tape, the cooperating contour between the strand and the weave of said tape being such as to retain the strand against displacement therefrom, and said strand including a spirally wound element arranged on said strand with the spirals of said element exposed and arranged in close proximity to each other, whereby each link of said stringer will contact at least one spiral turn of said element.

2. In a separable slide fastener comprising fastener stringers adapted to be coupled and uncoupled by a slider movable longitudinally thereof, each of said stringers comprising a stringer tape, an independent strand loosely arranged longitudinally of one edge of the tape in forming a beaded edge on the tape, coupling links secured to said edge of the tape and engaging said strand in supporting the strand on the tape,

and a spiral element arranged on said strand with the spirals of said element exposed in close proximity to each other whereby each link of the stringer tape will contact at least one spiral turn of said element.

3. A stringer for separable fasteners of the character described, said stringer comprising a tape, a plurality of cords loosely arranged longitudinally of one edge portion of the tape and on opposite surfaces thereof, said cords being attached to said tape solely by links cast directly on said edge of the tape at spaced intervals longitudinally thereof, said links extending onto both surfaces of the tape in a clamping manner serving to embed said cords in the surfaces of said tape, portions of said links penetrating into the interstices of said tape and cords preventing relative movement thereof, and at least one of said cords having a strand spirally arranged

thereon and exposed for contacting each of said links, thereby facilitating predetermined finishing treatment of said stringer.

4. A stringer for separable fasteners of the character described, said stringer comprising a tape, a plurality of strands loosely arranged longitudinally of one edge portion of the tape, said strands being attached to the tape solely by links die cast directly on said edge of the tape at spaced intervals longitudinally thereof and extending onto both surfaces of the tape, at least two of said strands being arranged on opposite surfaces of the tape, and at least one of said strands including a spirally arranged element having spiral turns exposed thereon sufficiently close to insure engagement with each link on said stringer, thereby facilitating predetermined finishing treatment of the stringer.

LOUIS H. MORIN.
